UNITED STATES PATENT OFFICE.

LOUIS WOJIDKOW, OF BROOKLYN, NEW YORK.

DESIGN FOR A CRUMB-TRAY.

SPECIFICATION forming part of Design No. 26,698, dated March 2, 1897.

Application filed January 25, 1897. Serial No. 620,702. Term of patent 3½ years.

To all whom it may concern:

Be it known that I, LOUIS WOJIDKOW, a citizen of the United States, residing at Brooklyn, in the county of Kings and State of New York, have invented and produced a new and original Design for Crumb-Trays, of which the following is a specification, reference being had to the accompanying drawings, in which—

- Figure 1 is a plan view of the crumb-tray. Fig. 2 is a sectional view on the line 2 2 of Fig. 1.

The leading feature of my design consists of a raised scroll-like border extending around three sides or edges of the tray, the two outer

scrolls forming compound curves and joining with the upper or central scroll.

Referring to the drawings, A represents the central and B B the outer scrolls, raised or struck up from the bottom C of the tray 20 and having their edges D bent or turned over, as shown. The outer scrolls form compound curves and join with the central scroll at a a.

What I claim is—

The design for a crumb-tray, as herein shown and described.

LOUIS WOJIDKOW.
